UNITED STATES PATENT OFFICE.

ANDREW F. SHULER, OF ARCANUM, OHIO.

BROODER.

1,346,688.

Specification of Letters Patent. Patented July 13, 1920.

Application filed February 10, 1920. Serial No. 357,532.

To all whom it may concern:

Be it known that I, ANDREW F. SHULER, a citizen of the United States, residing in Arcanum, in the county of Darke and State 5 of Ohio, have invented certain new and useful Improvements in Brooders, of which the following is a specification.

My invention relates to new and useful improvements in brooders, and has for its 10 object to provide an efficient and reliable brooder for brooding chicks under the most favorable conditions as to the character of fuel and the control of the temperature. To the above ends the improvements relate to 15 the coal burning brooder having features which enable the poultryman to care for a large number of chicks with a minimum amount of labor, and to means for regulating the temperature at all times, and a constant and proper supply of fresh air, as 20 hereinafter more fully described in connection with the accompanying drawings.

Figure 1 of said drawings is a top plan view of the hood or hover part of the same 25 being broken away.

Fig. 2 is a front elevation of the brooder, showing one-half of the hover elevated.

Fig. 3 is a top plan view of the stove and temperature regulating device.

30 Fig. 4 is a front elevation of the same.

Fig. 5 is a horizontal cross section through the upper part of the stove.

Fig. 6 is a vertical section of the upper part of the stove showing the check control, and

Fig. 7 is a sectional detail of the lower part of the stove showing the draft control.

In a more particular description of my invention like reference numerals will indicate like parts in the drawings.

The apparatus comprises a heat generator, which is a coal burning stove —1—, a temperature regulating device in the form of a thermostat —2— and a hood —3— beneath 45 which the chicks hover. The structural advantages and features of the above parts constitute the improvements by means of which the objects of my invention are attained. The stove —1— has a draft opening —4— in the base thereof below the grate —5—. Secured to the said base over the draft opening —4— is a horizontally extended arm —6— the secured end of which has an opening —7— which registers with the draft opening —4— and opens through 50 the upper side of said arm as at —8—. A

tilting arm or lever —9— has its inner end —10— constructed to form a damper —11— in connection with the draft opening —8—. The said arm —9— is fulcrumed at —12— 60 to the arm —6— and it has a screw —13— which passes through the free end thereof. Beneath the screw —13— and mounted on the end of the arm —6— is a thermostat —2—. The screw —13— may be adjusted 65 relative to the thermostat to regulate the position of the damper end —11— of the arm —9— relative to the draft opening —8—. The expansion of the thermostat, when sufficient, will close the damper and 70 when said thermostat contracts, the damper will be caused to open in proportion to the amount of contraction. The tilting arm or lever —9— is connected to a check damper —15— by a chain —16—. The check damper 75 —15— is hinged to an arm —17— extended from an elbow —18— which registers with an opening —19— in the upper part of the stove. The check damper —15— controls the draft through the stove according to the temperature as it affects the thermostat —2—. For example, when the damper —11— closes the draft inlet in the base of the stove, damper —15— is opened 80 and when the draft damper —11— is not under the control of the thermostat it is opened by the weight of the check damper —15— which always is closed when the temperature is not such as to expand the 85 thermostat.

The flue outlet —20— in the top of the stove as well as the air inlet —19— have on the interior of the stove baffle plates —21— and —22— respectively, which are secured in position by bolts —23— and provide 90 lateral passages —24— and —25— for the incoming air and outgoing products of combustion. A direct passage of air across the upper part of the stove, is thus avoided. At the top of the stove and on the exterior 100 opposite sides thereof are lugs —26— which serve as supports for the hood, when the same is in position to cover the chicks. The top of the stove has the usual removable plate which admits of the feed of coal. The hood or hover inclosure consists of two parts, which provide a suitable opening to receive the top of the stove. The said hood is constructed of suitable sheet metal and the metal surrounding the openings in each 105 part for the top of the stove is strengthened by a semi-circular metal piece —28—

the ends —27— of which project and have the form of eyes through which pass screws or pins —29— which enter the top of the stove and thus form hinges for the two parts of the hood to be raised and lowered upon. As is shown in Fig. 2 one half of the hood is raised and is temporarily held in such a position by means of a hook —30— on the edge thereof that extends around the smoke pipe —31—. When the parts of the hood are lowered they are supported in such positions upon the side lugs —26— on the upper sides of the stove. When lowered, the parts of the hood may be joined at their meeting edges by hooks —32— and thus held firmly together. The meeting edges of the two parts of the hood are provided with openings which, when the parts of the hood come together, provide an opening for the check draft elbow —18— to project through.

Having described my invention, I claim:

1. In a brooder of the type specified, a heat generator in the form of an upright stove, having a draft opening in the base thereof and a draft check opening in the top thereof, an arm extending from the base having an opening through the upper side thereof communicating with the said draft opening, an elbow communicating with the draft check opening, a lever pivoted to the arm having its inner end in the form of a damper which coöperates with the opening in said arm and whereby the draft is regulated, a thermostat controlling said lever, a damper for the draft check opening, and a flexible connection between said lever and said last named damper whereby the thermostat is adapted to control the positions of both dampers simultaneously.

2. In a brooder of the type specified, a heater in the form of an upright stove having a draft opening in the base thereof, and a check draft opening and an outlet for the escape of the products of combustion in the top thereof, an arm supported on the base thereof having an opening registering with said draft opening extending through the upper surface of said arm, a lever ful-

crumed on said arm having an end forming a damper which coöperates with the opening in said arm to regulate the draft, a thermostat mounted on said arm and adapted to actuate said lever to regulate the draft in 55 accordance with the condition of the temperature, a damper coöperating with the check draft opening, and a chain connecting said last named damper with said lever, said last named damper being adapted to 60 be opened through the action of the thermostat when the draft opening is closed thereby.

3. A brooder heater comprising an upright stove, having a draft opening in the 65 base thereof and a check draft opening in the top thereof, and an outlet in the top thereof for the outlet of the products of combustion, baffle walls arranged adjacent to the check draft opening and the opening 70 for the outlet of the products of combustion to deflect the air entering the check draft opening, and a thermostat adapted to control both draft and check draft openings.

4. A brooder heater comprising an upright stove having a draft opening in the base thereof, and a check draft opening and an outlet for the escape of the products of combustion in the top thereof, baffle walls 80 arranged between said check draft opening and said outlet to deflect the air entering the draft check opening, an arm supported on said base having an opening registering with the draft opening therein and extending through the upper side of said arm, a lever fulcrumed on said arm having an end forming a damper which coöperates with the draft opening in said arm, a thermostat mounted on said arm below said lever and adapted to actuate said lever to regulate the draft, a damper coöperating with the check draft opening, and a connection between said damper and said lever, the said damper being adapted to be opened through the action of the thermostat when the draft opening is closed thereby.

In testimony whereof I affix my signature.

ANDREW F. SHULER.
